UNITED STATES PATENT OFFICE

WILLIAM FINKELSTEIN, OF PHILADELPHIA, PENNSYLVANIA

TRAVELING BAG

Application filed October 12, 1926. Serial No. 141,104.

This invention relates to attachments for use in connection with valises, hand bags, traveling bags, suit cases, satchels and the like and has for its object the production of a new and improved lining for the same whereby a stronger bag is produced, and one which will more easily withstand outside pressure without losing shape and whereby the life of the bag proper will be generally increased.

In the present practice of making valises, hand bags and the like, the linings are attached directly to the bag structure and the lining and bag structure proper are both attached to the frame.

This results in certain disadvantages of which the following are pointed out:

First the lining cannot be removed from the inside of the bag without practically destroying the same, since it can only be removed by cutting the same away from the frame.

Secondly, since the lining cannot be removed from the inside of the bag without destroying the same, a soiled lining necessitates the purchase of a new bag while the outside bag structure is still strong.

Thirdly, since the lining cannot be removed from the frame the inside of the bag cannot be cleaned thoroughly.

It is further the general practice of making bags not to use any reinforcing structure for the bag per se. This results in a bag which cannot very easily withstand outside pressure and which would therefore readily lose its shape.

Where reinforcing structure is used it is in the shape of an attachment such as that shown in the U. S. Patent #1,028,168 to Williams, June 4, 1912.

It is one of the applicant's objects to produce an improved reinforcing structure which may be more easily made than the attachment disclosed by Williams aforementioned.

More specifically some of the objects of this invention are:

First to produce a new and improved lining for valises, hand bags, traveling bags, satchels

and the like and which reinforces the bag structure.

Secondly to produce a removable new and improved lining for valises, hand bags, traveling bags, satchels and the like.

55

Thirdly to produce a new and improved reinforcing means for the body of valises, hand bags, traveling bags and the like.

Fourthly to produce a new and improved bag whereby only a portion of the lining is removable if desired.

With the foregoing and other objects in view which will appear as the description proceeds, the invention, without limiting intention, resides in the combination and arrangement of parts and in the details of construction hereinafter described and claimed.

65

In the accompanying drawings, in which the preferred form of the invention has been shown,

70

Figure 1, is a perspective view of the reinforcing and bracing means detached from the lining.

Figure 2, is a sectional view taken on the line 2—2 of Figure 1.

75

Figure 3, is a sectional view taken on the line 3—3 of Figure 1.

Figure 4, is a perspective view of the removable lining per se.

80

Figure 5, is a perspective view of the removable lining associated with the reinforcing structure parts being broken away to more clearly bring out certain details of construction.

85

Figure 6, is a sectional view taken on the line 6—6 of Figure 5.

85

Figure 7, is a schematic perspective view of the bag and lining combined parts of both the bag and lining being broken away to more clearly bring out details of construction.

90

Figure 8, is a top view of one of the top bracing elements shown in Figure 1.

95

Figure 9, is a schematic sectional view taken on the line 9—9 of Figure 7 parts being left out for the purpose of clearness.

Referring more specifically to the figures wherein like reference numerals denote similar parts, reference numeral 1 denotes the reinforcing and bracing framework to which

100

the removable lining is attached and which supports the same.

The framework 1 consists of a plurality of **U** shaped body members 2, and of two **U** shaped top members 3. These are preferably made of resilient material such as spring metal but need not necessarily be made of that since any material having the necessary qualities of rigidity and a certain amount of elasticity may be used. The ends of the **U** shaped body members 3, are bent over and around the top **U** shaped members 2, and are secured to the main body members 2 by rivets 5, or other connecting means thus forming the loops 4 in which are carried the top members 3. Riveted or otherwise attached to the members 2 is a strip 10 which serves as a spacer for the said members and also to prevent lateral movement of the same.

Reference numeral 6 denotes the removable lining.

This may be made of leather, cloth, leatheroid or any other material desired and in its preferred form is a bag like structure having side walls 7 and 7' and a bottom 8. The top of the side walls 7 and 7' are bent upon themselves to form the loops 9 which serve to carry the top bracing members 3 of the assembly 1. Auxiliary strips 11 are attached to the walls 7' in the manner shown to form the pockets 12.

Attached by stitching or otherwise at desirable points along the top of the sides 7' are the auxiliary leather flaps 13 which serve as an aid when it is desired to remove the removable lining from the bag.

Attached by stitching or otherwise to the top of the sides 7 of the bag are the leather tabs 14 carrying the male member 15 of a fastening snap which cooperates with a female member situated at a suitable cooperative point on the bag proper to keep the bag and lining together.

It is to be understood that the disclosure as to situation of the tabs 13 and 14 are merely for the purposes of illustration and not by the way of limitation.

The bag per se 18 is the well known type of valise, hand bag, satchel or the like with the exception of the fact that it has no lining. However the applicant's attachment could be used with bags having linings as an auxiliary bracing frame and lining protector.

In assembling the removable lining structure the lining portion 6 is generally put within the **U** bracing members 2 and the loops 9 of the lining portion encompass the top bracing 3 as shown (see Figure 5) the looped part of 17 of the lining portion being secured to the main walls 7 and 7' by rivets 16 or by stitching or other means. The completed assembly is designated 6'.

In assembling the removable lining assembly 6' with the bag portion 18, the former is inserted into the latter the top members 3

being placed under the frame elements 19 of the bag as shown in Figures 7 and 9. The reinforcing members 2 being resilient assume the shape of the bag as shown in Figures 7 and 9 at the same time being put under compression. This serves to both force the side walls of the bag outward, thus helping it to keep its shape and to help the bag to resist lateral compression, and also serves to press top members 3 against the bag frame elements 19 thus serving to keep the removable lining structure 6' in place and also to resist vertical compression. The frame element being constructed as shown serves to evenly distribute any pressure. To prevent relative motion between the bag and removable frame assemblies the two are attached together by means of the snap hook fastening means 15 and 15' situated the auxiliary tabs 14 and 14' attached to the removable lining and bag structures respectively as shown in Figure 9 where the auxiliary tab 14' is shown overlying the auxiliary tab 14.

It is to be understood that wherever necessary rivets or other binding means are used to keep separate pieces firmly united together.

It is to be further understood that the above disclosure is by the way of illustration only and not by the way of limitation since many changes may be made without departing from the scope of the invention described above and claimed in the following claims:—

Definitions.—The word "integral" as used in the claims and specifications is used to denote a continuous member, such as **U** shaped body member 2, whether formed of a single piece or a plurality of pieces joined together by riveting, welding or the like to constitute a continuous unit.

What I claim is:—

1. As an article of manufacture a valise, hand bag, traveling bag, satchel and the like consisting of the combination of a bag and frame portion with a removable lining portion, the said lining portion having fixed associated therewith auxiliary stiffening members.

2. As an article of manufacture a removable lining adapted to be inserted in valises, hand bags, suit cases and the like, the said lining comprising a bag like lining portion and auxiliary stiffening means associated with said lining and encompassing the same.

3. As an article of manufacture a removable lining adapted to be inserted in valises, hand bags, suit cases and the like, the said lining comprising a bag-like structure and resilient metallic stiffening means associated with the said bag-like structure, the said stiffening means comprising a plurality of integral members, the said integral members encompassing the said bag-like structure on its three closed sides, the said stiffening means further comprising a second member, the said

second member encompassing the "mouth" or open portion of the said bag-like structure.

4. As an article of manufacture a removable lining adapted to be inserted in valises, hand bags, suit cases and the like, the said lining comprising a bag-like structure and resilient metallic stiffening means associated with the said bag-like structure the said stiffening means comprising a plurality of integral members, the said integral members encompassing the said bag-like structure on its three closed sides, the said stiffening means further comprising a second member, the said second member encompassing the "mouth" or open portion of the bag and attaching means attaching the first said stiffening members to the second said stiffening members and each of said members to the said bag-like structure.
5. As an article of manufacture a removable lining adapted to be inserted in valises, hand bags, suit cases and the like, the said lining comprising a bag-like structure and resilient metallic stiffening means associated with the said bag-like structure, the said stiffening means comprising a plurality of integral members, the said integral members encompassing the said bag-like structure on its three closed sides, the said stiffening means further comprising a second member, the said second member being composed of two sections, the said sections encompassing the "mouth" or open portion of the bag and attaching means attaching the first said stiffening members to the second said stiffening members and each of said second stiffening members to the said bag-like structure.

6. An attachment for valises, hand bags, traveling bags, suit cases or the like comprising a frame, the said frame comprising a top frame comprising two integral sections, and a plurality of side-and-base frames attached thereto, each of the said side-and-base frames being formed of integral pieces of resilient material.

7. An attachment for valises, hand bags, traveling bags, suit cases or the like comprising a top frame and a plurality of U shaped side-and-base frames attached thereto, the said top frame comprising two integral U shaped sections, and each of the said side-and-base frames being formed of an integral piece of resilient metal.

In testimony whereof I affix my signature.

WILLIAM FINKELSTEIN.
